It is certified that error appears in the above-identified patent and that said Letters Patent is hereby corrected as shown below:

Title page.

After Item [56], please insert the following: -- This application is a continuation in part application based on presently pending U.S. Provisional Patent Application Serial No. 60/369,858 filed on April 5, 2002, and bearing the title "SURGICAL CART."

Be it known we, Udo Warschewske, Karl-Heinz Reinwald and Peter Korn have invented a new, original and ornamental design for SURGICAL CART, of which the following is a specification, reference being had to the accompanying drawings forming a part thereof. --

Item [57], **DESCRIPTION**, reads "FIG. 1 is a front perspective view of a surgical cart" and should read -- FIG. 1 is a front perspective view of a first embodiment of the cart --; and reads "FIG. 7 is a bottom of the cart." and should read -- FIG. 7 is a bottom view of the cart --.
